UNITED STATES PATENT OFFICE.

ALEXIS W. BEARCE, OF NIAGARA FALLS, NEW YORK, ASSIGNOR TO WILLIAM A. ROGERS, LIMITED, A CORPORATION OF ONTARIO, CANADA.

DISPLAY APPLIANCE.

Application filed May 15, 1922. Serial No. 561,107.

To all whom it may concern:

Be it known that I, ALEXIS W. BEARCE, citizen of the United States of America, residing at Niagara Falls, in the county of 5 Niagara and State of New York, have invented certain new and useful Improvements in Display Appliances, of which the following is a specification.

This invention relates to display appliances. A display appliance involving the invention can with advantage be used in a variety of connections. For instance, it can be used for receiving and showing for exhibition or storage purposes, silverware of 15 various kinds such as knives, forks or spoons. Among the principal objects of the invention are the provision of an article of this character which can be readily and inexpensively produced and which is as stable, 20 as practicable, and by which the articles cannot only be readily mounted, but as quickly dismounted either for use or for sale.

In the drawing accompanying and forming part of the present specification I have 25 shown in detail one of the several forms of embodiment of the invention which to enable those skilled in the art to practice the same will be set forth fully in the accompanying description. Obviously I am not 30 restricted to this disclosure. I may depart therefrom in a number of particulars within the scope of the invention defined by the claim following said description.

Referring to said drawing:

35 Fig. 1 is a top plan view of the upper portion of the device with parts broken away.

Figs. 2 and 3 are transverse sections on the lines 2—2 and 3—3 respectively of 40 Fig. 1.

Like characters refer to like parts throughout the several views.

The article preferably but not essentially, involves in its construction a box comprising 45 a body as 2 which may be made of proper material, such as pasteboard, furnished with a removable lid 3. It may not in all cases be necessary to provide a box and where there is a box, it need not necessarily have a lid 3. Fitted in the box body 2 when the same is present, is a pad 4. This pad usually comprises a body of proper formation such as a rectangular sheet or piece of pasteboard, or equivalent material,

partly covered with some fabric, which may 55 be silk, satin, velvet or paper, or the body of the pad may be merely painted or plain if desired.

Through this pad and extending transversely thereof is shown the virtually rectangular and somewhat elongated slot 6 which functions as I will hereinafter explain. Associated with the pad 4 is a rack such as that denoted in a general way by 7. This rack comprises a body as 8 practically 65 in plan desirably of the same shape as the slot 6, the body 8 being generally covered with fabric as 9 which may be of the same color as the fabric or paper 5 on the pad 4. The body 8 has in it the cuts or notches 10 generally diagonal to the longitudinal axis thereof and which are of a width and depth to properly receive the articles to be displayed. 70

The superficial area of the fabric 9 is 75 somewhat greater than that of the upper surface of the body 8 for a reason that will hereinafter appear. This fabric 9 may be the same color as that of the fabric 5 when the latter is present, or may be of a contrasting shade. 80

Initially the pad 4 has attached thereto, the facing or fabric 5 in which is usually held thereto by glue, the slot 6, extending, of course through the fabric 5, which constitutes the exposed surface of the pad. The body 8 will then have placed upon its upper side the covering fabric 9 which is pressed down into the several transverse slots 10 until it bottoms therein. The fabric 9 is then brought against the side faces and the ends of the body 8, subsequent to which said body 8, with the fabric 9 thereover, is passed from the lower or inner side of the pad 4, through the slot 6, the walls and ends of the slot 85 smoothing the sides and ends of the fabric. This fastens the rack 7 firmly in position. The pad 4 is then gummed or otherwise suitably attached to the upper surface of the bottom of the box body 2. 95

100 In addition to the article I will also as a part of the invention claim the method of making it.

What I claim is:

105 In a device of the class described, a pad having a slot between the upper and the lower and the side edges thereof, and a rack involving a notched body and a covering for

the body, the covering being projected into the notches of the body, and the body and its covering being projected through said slot from one side of the pad so as to project from the opposite side of the pad with the covering extending over the sides and the ends and the upper surface of the body

and into the slotted portion of said body.
In testimony whereof I hereby affix my signature.

ALEXIS W. BEARCE.
